Primary Examiner — Caron D Veynar*Assistant Examiner* — Kelley Donnelly(74) *Attorney, Agent, or Firm* — Santangelo Law Offices, P.C.(57) **CLAIM**

The ornamental design for a tripod stand, as shown and described.

DESCRIPTION

FIG. 1 shows a top view of a tripod stand.

FIG. 2 shows a front view thereof.

FIG. 3 shows a rear view thereof.

FIG. 4 shows a top view thereof; and,

FIG. 5 shows a bottom view thereof.

It is of note that any broken line illustration of environmental structure in the drawings is not part of the design sought to be patented.
